UNITED STATES PATENT OFFICE.

BENJAMIN B. BIENHOFF, OF MINNEAPOLIS, MINNESOTA.

DISPLAY APPARATUS.

1,256,431.

Specification of Letters Patent. Patented Feb. 12, 1918.

Application filed March 16, 1916. Serial No. 84,747.

To all whom it may concern:

Be it known that I, BENJAMIN B. BIENHOFF, a citizen of the United States, residing at Minneapolis, in the county of Hennepin and State of Minnesota, have invented a new and useful Display Apparatus, of which the following is a specification.

My invention relates to display apparatus and more particularly to the displaying of flexible signs, etc., which are used in advertising purposes. I use a simple supporting means and the signs travel from front to the back of the machine in consecutive order during the operation of the machine.

15 A primary object of this invention is the use of a single pair of carrying chains which make my device very simple and positive in operation.

Further objects of my invention are means 20 for holding the carrying chains rigid when lifting a sign and means forming a part of the chain for receiving the ends of the rods carrying the signs and holding them beyond the center of the pivoted points of 25 the chain, thus causing the rods to tend to lock themselves into the notched links of the chain rather than twist the chain in the opposite direction and allow the rods to fall out of the engaging links.

30 It is also an object of my invention to have a portion of the ends of the rod which carry the signs squared so as to prevent climbing, as they are held adjacent to each other on the supports in the frame.

35 In the drawings forming part of this specification, Figure 1 is a vertical section in side elevation of my invention.

Fig. 2 is a sectional plan view of Fig. 1, taken on the lines X—X, showing one-half 40 of the same, as both sides of the machine are identical.

Fig. 3 is a vertical front section in elevation of a portion of my machine.

Fig. 4 is a detail showing the discharge of 45 the sign carrying rods on to the supports.

Fig. 5 is a detail of the carrying chain and a portion of the guide to hold the lifting chain and notched link.

Fig. 6 is a perspective of one end of the 50 rods which carry the signs.

In the drawings, A represents an inclosing frame having back 1, front 2, top 3, bottom 4 and ends 5. The front 2, has an opening 6, which may be covered by a glass 7, and 55 through which the signs are displayed. Declining downwardly toward the front of the

frame A and secured to the opposite sides 5, are supports 8, which carry the sign supporting rods 10.

The flexible signs B are adapted to be detachably held in the rods 10, by a split pin 9, or any other suitable manner. Near the outer end of the rods 10 is a squared portion 11, which is adapted to lie adjacent to the squared portion of the adjacent rods as a 60 plurality of rods are held on the supports 8; thus preventing the tendency of climbing over each other, as the rods travel by gravity down the declining support 8, when the foremost sign is lifted and passed to the back of 70 the series and deposited on the support 8 again.

The rods 10 are formed with a circular end 12, of the same diameter as the thickness of the squared portion 11, which rests on the 75 supports 8, to hold the signs in position in the frame A.

A portion 13, of the rods 10 is of smaller diameter than the ends 12, which allows the easy engagement of the rod by the hook on the 80 carrying or lifting chain.

It is obvious that wheels may be used on the ends of the rods 10, in place of the circular portion 12, to eliminate most of the friction in the travel of the rods from the front 85 to the back of the supports 8.

The supports 8 are formed with stops 14, on their forward end, which hold the foremost sign in displaying position.

The rods 10, and their signs are carried, 90 one at a time, from the displaying position at the front of the supports to the rear of the series by means of a pair of endless carrying chains 15, which travel over the sprockets 18, 19, 20, 21, 22 and 45. 95

The sprockets 20 and 21, are mounted upon shafts 23 and 24, respectively, which extend across the inclosed frame A near the top.

The sprockets 22 are secured to the horizontal shaft 26, which extends across the 100 frame A and is held free to move up and down in the U-shaped bearings 24, which are mounted on the sides 5 of the frame, thus keeping the carrier chain taut at all times.

The idle sprockets 19, are freely journaled 105 upon gudgeons 25, which are mounted in any suitable manner on the sides 5 of the frame and the sprockets 18, are freely journaled on the gudgeons 27, which are secured on the sides 5 of the frame.

110 On one side of the frame A the sprocket 18, has a pulley, rigidly connected therewith, in

any suitable manner, as is illustrated in Fig. 1. By means of a driving belt D, the pulley may be connected with an electric motor C, or any other motive power, to drive the 5 chains 15, in the direction of the arrows, illustrated in Fig. 1.

The sprockets 45, are freely journaled on gudgeons which are secured to the supports 8, thus allowing free passage of the signs B, 10 as the ends of the rods 10 are deposited on supports 8.

The sprockets 20 and 21 are rigidly secured to the shafts 23 and 24, and the shafts 23 and 24, are journaled in any suitable 15 manner on the opposite sides 5 of the frame, thus the chains 15 will be driven in unison at all time.

Rollers 28 and 29 are freely journaled on the horizontal shafts 23 and 24 respectively 20 and extend the full length between the pairs of sprockets 20 and 21, and as the signs B are carried from the front to the back of the frame they drag on these rollers which keeps them straight without causing any 25 excessive friction and roller 29' which is freely journaled on the shaft 26 and extending between the sprockets 22 across the machine assists to turn the signs over easily as they go down and around the roller 29' and 30 thence upward and deposited upon the supports 8 with the display surface forward.

The width of the frame A is just a trifle greater than the length of the rods 10, thus the sides 5 of the frame A act as a guide to 35 the rods as they are moved from one position to another.

The pairs of chains 15 are composed of the ordinary links and each chain 15 has a link E which is positioned directly opposite 40 the link E on the other chain and travels in synchronism therewith. One side 32, of the links E being in the form of a loop with a recess 33, and the other side 34, being formed with a forwardly projecting hook 45 or engaging end 35, and backwardly projecting portion 36.

The portion 36 is adapted to carry two horizontally projecting rollers 37, which are freely journaled on the gudgeons 38 and 50 adapted to travel in the guides 39, which are secured to either side 5 of the frame A.

The sides 34 of the links E have a similar 55 recess 33, as in the side 32, which is adapted to receive the portion 13 of the rods 10, when the hook 35 engages the foremost rod.

Angularly formed guards 41, are secured to the walls or sides 5, a portion of which is parallel to the supports 8 and positioned far enough above the same to form a free 60 passage-way for the ends 12 of the rods 10, but serving to prevent the rods from raising up off the supports until they reach the foremost position on the supports 8.

The guards 41 are bent up near the forward end of the supports 8 to form a pas-

sage way 42 between the stops 14 and the guards 41 to allow the foremost rod 10 only to be lifted off the supports 8 by the engaging links E of the chains as they pass the rods in the operation of my apparatus. 70

The guards 41 continue upward and curve outward to be in line with the inner edge of the chains 15, thence continuing in the same direction and the same horizontal plane as the inner edge of the chains 15, thence to the 75 back of frame A, around sprocket 21 and down around the sprocket 22, then up to the sprocket 45. (See Fig. 1).

Thus in operation the chains 15 will travel upward in the direction of the arrows and 80 the rollers 37 enter the guides 39 and as the hooks 35 engage the portion 13 of the foremost rods 10 the guides 39 will hold the hooks rigid until the rod is lifted from the support 8, and slides into the recesses 33 of 85 the links E, the guards 41 assisting in pushing it into the recess 33 and as the link E carries the rod up around sprocket 20, the ends 12 of the rod 10 will rest on the guards 41 to prevent its falling out of the recess 33. 90

The guards 41 also serve to hold the rod in the recesses 33, as it travels with the chains 15, down the back of the machine and around sprocket 22 and up to sprocket 45. One of the teeth of the sprockets is cut 95 away, so as not to bind the end of the rod 10 as it passes around the sprockets, and the end 12 of the rod 10, engages the upper rear edge 46 of the supports 8 which is cam shaped, and thereby forcing the rod out of 100 the recesses 33 unto the back of support 8, placing it at the back of the series of rods 10, with its same display surface facing forwardly as illustrated in Fig. 4.

When the foremost rod is removed with 105 its sign B, the next rod and sign slide by gravity into its place against the stops 14 and its sign or display surface is displayed through the aperture 6, until the links E travel around and engage it and carry it to 110 the back of the series.

The operation is continued in this manner displaying the signs, one after the other, over and over again, is positive in action and simple in operation. 115

While I have used one particular form of frame and construction to illustrate my invention, I do not wish to confine myself to this particular form, which is only illustrative and the invention can be carried out by 120 other means and applied to other uses within the scope of the following claims.

Having described my invention, what I claim is:—

1. In a display apparatus, comprising, an 125 inclosing frame, declining supports in said frame, a series of rods adapted to rest on said supports, each of said rods carrying a flexible sign, means for carrying the foremost rod with its sign upward, and from 130

the front to the back of said frame, said carrying means comprising a pair of chains having a pair of recessed links which are adapted to engage the ends of said foremost 5 rod, and means formed on said recessed links for holding said links and chain rigid in a vertical plane while lifting and receiving said rod in said recessed links.

2. In a display apparatus, comprising, an 10 inclosing frame, declining supports in said frame, a series of rods adapted to rest on said supports, each of said rods carrying a flexible sign, means for carrying the foremost rod with its sign from the front to 15 the back of said supports, and said supports being formed with a semi-circular cam-shaped rear end which is adapted to begin to engage said rod while still in said carrying means, and to completely force 20 said rod free of said carrying means, when said carrying means has delivered said rod to the topmost point of said support, substantially as described.

3. In a display apparatus, comprising, an 25 inclosing frame, declining supports, secured to the sides of said frame, a series of rods resting with their ends upon said supports, each carrying a depending flexible sign, a pair of endless carriers disposed on opposite 30 sides of said frame, a pair of links forming a part of said carriers, each having a hook formed on one side and recesses in both sides of said links, said hooks being adapted to engage the ends of said rods and allow them 35 to slide into said recesses, the back of said hook being formed with an outwardly projecting portion, upon which are freely journaled rollers, a guide secured to the wall of said frame into which said rollers are 40 adapted to slide when said links are lifting said rods off of the forward ends of said supports, and thereby hold said links and carrier rigid in a vertical plane, substantially as described.

4. In a display apparatus, comprising, an 45 inclosing frame, declining supports in said frame, a series of rods adapted to rest on said supports, a pair of chains having a pair of recessed links adapted to engage 50 the ends of the foremost rods on said supports, a guard above the forward end of said support lying parallel thereto, and ex-

tending upwardly at the forward end of said support to allow a passage for the foremost rod resting on said support, said 55 guard curving forwardly toward said chains, so as to engage the ends of said rod while said rod is being lifted from said supports by said links, and forcing said rod into said recesses, said guard extending parallel with said chains to the back of said supports and adapted to hold said rod, and means formed on the ends of said supports for disengaging said rod from said links to deposit said rod on the rear of said supports.

5. In a display apparatus, comprising, an 60 inclosing frame, declining supports on either side of said frame, a series of rods adapted to rest on said supports, and each of said rods carrying a flexible sign, a pair of chains having a pair of recessed links, one side of each of said links having a forwardly projected hook thereon, an elongated portion formed near the end of said rods of a smaller diameter than the ends of said rods, 75 and a squared portion formed on said rods which is adapted to space the rods apart, so as to form a space between said elongated portions of the adjacent rods, thereby allowing the engaging end of said hooks 80 on the recessed links to pass between the first and second rod on the supports to engage one rod at a time, said links adapted to carry said rods to the back of said supports, and to turn said sign over, so that the 85 same display surface will face forwardly in said frame.

6. In a display apparatus, comprising, an 90 inclosing frame, declining supports in said frame, a series of rods adapted to rest on said supports, a pair of chains adapted to travel over a series of sprockets in said frame, a pair of recessed links on the inside of said chains forming part of said chains adapted to engage the foremost of said rods 95 resting on said supports, and carry it over some of said sprockets to deposit said rod on the rear of said supports, said sprockets over which said rod is carried having some of the teeth removed, so as not to bind said 100 rod as it passes over the same, substantially as described.

BENJAMIN B. BIENHOFF.
